FIG. 5

1
STOCK ANALYZER

This invention relates to a novel stock analyzer and a method of analyzing stock. The application is a continuation-in-part of my earlier co-pending application, Ser. No. 94,680, filed Dec. 3, 1970, now abandoned.

In the stock analyzer and method of the present invention standards are set for evaluating certain specific data pertaining to the stock to be evaluated, for example, in respect to the exchange on which the stock is traded, the price/earnings ratio, yield, etc., and these values are introduced into a storage system in which they are totaled and translated into a buy or sell reading on an indicator.

For a complete understanding of the present invention reference can be made to the detailed description which follows and to the drawings, in which:

FIG. 1 is a perspective view of one embodiment of the stock analyzer of the present invention;

FIG. 2 is a schematic view of the circuit diagram of the stock analyzer shown in FIG. 1;

FIG. 3 is a perspective view illustrating a weight used in conjunction with the stock analyzer shown in FIG. 1;

more weight is added to the movable platform, the movable contact 21 will move out of engagement with the contact 23 and into engagement with the contact 24, thereby conditioning the Sell lamp for operation. As more weight is added to the platform, the contact 21 will move into engagement with the contact 25, conditioning the Hold lamp for operation, and then into engagement with the contact 26, conditioning the Buy lamp for operation. For greater suspense, the weights can be added to the platform with the switch 20 open so that the operator will not know what the recommendation of the stock analyzer is until he has completed the analysis and closes the switch 20.

In the use of the stock analyzer an assortment of weights is provided, for example, weights of 2½ oz., 1½ oz. and ½ oz., identified by the colors red, yellow and black, respectively, on their heads 14a. In analyzing a particular stock, weights are assigned on the basis of specific data relative to the stock, for example, the exchange on which the stock is traded, the price/earning ratio, yield, etc. The following chart illustrates an assignment of the weights on the basis of information available in Standard and Poor's handbook.

Color code	Where traded	Cur. mkt. price to high for cur and past year	Previous months volume to outstanding shares (percentage)	P/E ratio	Consec. yield for -	Assets to liabilities	Total outstanding shares	Consec. yearly earnings	Earnings for last reporting period	Good or exciting news	How many years in business
Red.....	NYSE.....	50% or less.	10% or more.....	Under 9 to 1.	Over 3 yrs.	3 to 1 or more.	Under \$1 mill.	5 or more.	Up over 20%.	Yes—announced by co.	Over 10.
Yel.....	AMEX.....	80% or less.	5% to 9%.....	9-12 to 1....	3 yrs. or less.	1 to 3 to 1.....	\$1-2 mill....	3-4.....	Increased from 0-20%.	Maybe (rumor).	5-10.
Black.....	Other.....	At high.....	Less than 5%.....	Over 12 to 1.	None.....	Under 1 to 1.	Over \$2 mill.	Under 3...	Decreased.	None.....	Under 5.

FIG. 4 is a schematic circuit diagram illustrating another embodiment of the stock analyzer; and

FIG. 5 is a schematic view of the circuit diagram of still another embodiment of the invention.

The stock analyzer illustrated in FIGS. 1 to 3 of the drawings includes a housing 10 containing a scale 11 which has a movable platform 12. The top of the housing contains a plurality of spaced apart openings 13 directly above the movable platform of the scale. Elongated weights 14 having selectively colored heads 14a can be dropped onto the movable platform of the scale through the openings, leaving the upper ends of the weights visible and accessible to the operator.

The housing accommodates a plurality of indicating means which in the preferred embodiment of the invention are lamps 15, 16 and 17 indicating, respectively, "Sell", "Hold" and "Buy." Also, to make it possible for the instrument to be checked to insure that it is in an operable condition, a test lamp 18 is also provided.

The lamps 15, 16, 17 and 18 are arranged in parallel in a circuit which includes a source of electric potential 19, an on-off switch 20 and a movable contact 21 carried by the platform. The lamp 18 is connected in series with a test switch 22.

When the platform 12 is in its fully raised position, the movable contact 21 will engage the contact 23, conditioning the test lamp 18 for operation. When the test switch 22 is closed, the lamp 18 should light, indicating that the stock analyzer is ready for operation. As

In addition, weights can be assigned on the basis of whether the company is a manufacturer of staple goods (red), such as drugs, food, oil, etc., a glamour stock (yellow), such as laser beam technology, air pollution, etc., or a speculative stock (black).

When the analysis is completed on the basis of the information pertaining to the particular stock, it may be desirable to take into account additional factors, such as the current condition of the market, the condition of the particular industry, the length of time which the stock is to be held, etc. Although the weight to be accorded to these factors depends to a large extent on the judgment of the operator, the dials 27 and 28 on the housing are provided to assist him. The upper dial 27 has a pointer 27a which can be moved relative to a scale 29. The dial 27 also carries an extension 27b divided into areas red, yellow and black designating weight magnitudes. The dial 28 also has a pointer 28a which is movable relative to a scale 30 and a pointer 28b which points to one of the areas of the extension 27b and thereby designates the additional weight to be added.

In the preferred method of operating the stock analyzer illustrated in FIGS. 1 to 3 of the drawings, the dial 27 is adjusted in accordance with the recent performance of the stock market. For example, if the Dow-Jones industrial average is on the rise, the dial 27 would be moved one or more points in the plus direction, whereas if it is on the decrease, that would be consid-

ered a negative factor. The bottom dial 28 can be adjusted on the basis of the performance of the industry and the length of time which the stock is to be held. For example, if the performance of the industry has been good, that would be regarded as a plus factor. Also, if the investor intended to hold the stock for a long period of time, he would add a plus factor. When these judgment corrections have been made, the appropriate weight indicated by the pointer 28b is added to the scale. By closing the switch 20, the operator can determine whether to sell, hold or buy by the glow of the appropriate lamp.

In the embodiment of the invention illustrated in FIG. 4 of the drawings, the movable contact 21 carried by the platform 12 serves as the sliding arm of a potentiometer which registers a Sell, Hold or Buy reading on a voltmeter 31 depending upon the displacement of the movable contact relative to a resistance 32. The resistance 32 is connected in series with a control switch 33 and a battery or other source of electric potential 34. The voltmeter is connected to the upper end of the resistance by a lead 35 and to the movable contact 21 by a lead 36 which has sufficient slack in it to permit the movable contact to move downwardly along the resistance as additional weight is added to the scale. As the weight on the scale increases and the movable contact 21 moves downwardly relative to the resistance, the voltage reading on the voltmeter will increase. By calibrating the dial on the voltmeter into Sell, Hold and Buy readings, when the switch 33 is closed the voltmeter will indicate whether to sell, hold or buy the stock which is being analyzed.

In the embodiment of the invention illustrated in FIG. 5, the stock analyzer of the present invention includes a housing containing a plurality of multiposition selector switches 41 capable of introducing a variable measure into a storage system which is ultimately totaled and the total measure translated into a buy or sell reading on an indicator. The storage system of this embodiment utilizes variable resistances in lieu of the variable weights utilized in the embodiments of FIGS. 1 through 4.

Toward this end, the housing accommodates an electrical circuit which is shown schematically in FIG. 5 of the drawings. Each multi-position switch 41 is adjustable from a "zero" or "off" position to "on" positions "1", "2" or "3". The "on" position "1" selects a resistor 43 of higher resistance, the on position 2 selects a resistor 44 of lower resistance, and the on position 3 selects a resistor 45 of still lower resistance. When all of the multi-position switches 41 have been adjusted to their selected on positions in accordance with the prescribed standards of evaluating each of the factors of

the stock which is to be analyzed, the operation of a read switch 46 completes a circuit from a power supply 47 through the entire bank of selected resistors connected in series to register on an ammeter 48. Since the selected resistors decrease in resistance as the information about the stock is more favorable, the current flowing through the selected circuit will be higher if the stock is a good prospect for purchase and lower if the stock is a poor prospect for purchase. The ammeter, therefore, can be calibrated to show a sell reading when the current flow is below a certain level and a buy reading when the current flow is above that level.

The invention has been shown in preferred forms and by way of example only, and obviously many modifications and variations may be made within the spirit of the invention. The invention, therefore, is not to be limited to any specified form or embodiment except insofar as such limitations are expressly set forth in the claims.

I claim:

1. A stock analyzer comprising an indicator having a "buy", "sell" reading, an information storage system for accommodating and totaling a plurality of different measures of information about the stock to be analyzed, a plurality of variable electrical components in said information storage system for introducing into said storage system the measures to be totaled with respect to a particular stock, adjustable means for varying each electrical component, and means for translating the total of the variable measures into a buy or sell reading on the indicator.

2. A stock analyzer as set forth in claim 1 in which the means for translating the total measurement into a buy or sell reading on the indicator includes a source of electrical power, means connecting the electrical components in series with the source of electrical power and means connecting the indicator in series with the source of electrical power and the electrical components.

3. A method of analyzing stocks comprising accumulating in an information storage system a plurality of different measures of information about a stock to be analyzed by adjusting variable electrical components for introduction into the information storage system, measuring the quantum of such variable measures introduced into the information storage system by connecting all of the electrical components for indicating the measured quantum of such variable measures and indicating the measured quantum of such variable measures to show whether the stock is a prospect for purchase or sale.
